UNITED STATES PATENT OFFICE.

WILLIAM S. HAMM AND ANTHONY M. DUBURN, OF CHICAGO, ILLINOIS,
ASSIGNORS TO THE ADAMS & WESTLAKE COMPANY, OF ILLINOIS.

TUBULAR LAMP.

SPECIFICATION forming part of Letters Patent No. 514,927, dated February 20, 1894.

Application filed April 15, 1893. Serial No. 470,446. (No model.)

To all whom it may concern:

Be it known that we, WILLIAM S. HAMM and ANTHONY M. DUBURN, citizens of the United States, residing in Chicago, in the county of Cook and State of Illinois, have invented certain new and useful Improvements in Tubular Lamps, of which the following is a specification, reference being had to the accompanying drawing.

10 This invention relates to tubular lamps and more particularly to that class used upon street cars both open and closed, for illuminating purposes. A fruitful source of annoyance and objection in this class of lamps is the liability of extinguishment thereof by sudden or strong gusts of wind due to various causes, a principal cause being the counter-currents near the top of the globe, which cause a choking or reversing of the air currents supplying the burner.

15 The prime object of this invention is to avoid this difficulty by providing the lamp with means whereby the production of counter-currents is avoided and the air properly directed into the air-ducts in both a cold and partially heated condition.

20 This invention may be applied to lamps of any suitable construction and irrespective of any particular kind of burner and its connecting and operating devices, the lamp illustrated in the accompanying drawing being simply a type of the class to which our invention may be best applied.

25 The primary objects of this invention are attained by the devices illustrated in the accompanying drawing, in which is shown a sectional elevation of a lamp embodying our invention.

30 Similar letters of reference indicate the same parts in the drawing.

Referring by letter to the accompanying drawing, A designates the globe, B the chimney, C the inductor and E the air-ducts all of which may be of any well known or desired construction.

35 The chimney B is provided with a depending vertical flange F having an annular series of slots G therein and an oblique deflecting plate H whereby the products of combustion are separated, the inner portion thereof

going out through the chimney proper, while the outer portions thereof contiguous to the globe and consisting principally of hot air, are deflected out through the slots G into the chamber between the slotted flange F and the inductor, from whence they pass into the air-ducts E and thence down to the burner. The upper end of the globe bears against or engages the lower edge of the slotted flange F as shown, so as to form a practically air-tight joint at that point. Between the slotted flange F and the inductor C is a space or chamber from which lead the air-ducts and into which chamber the cooler, outer atmosphere is taken at the bottom of the inductor and also over the top thereof, as shown, the reflector I being provided with a suitable opening permitting the air immediately surrounding the globe to pass up into the chamber at the under side of the inductor. The inductor is provided with an oblique inwardly and downwardly extending flange J which extends nearly to the chimney B, and immediately above the inductor is located a flaring shield or collar K having the general shape of an inverted truncated cone, the lower and smaller end of which terminates immediately above the inductor and is of less diameter than that of the top of the inductor, but preferably not less than the diameter across the lower edge of the oblique flange J. This flaring shield or collar may be supported from the inductor by the arms L, or if desired, it may be attached directly to the roof of the car. This shield or collar K directs a current of air downwardly into the inductor over the oblique flange thereof, which current being met by the upward current from the under side of the inductor, unites therewith and passes from the chamber between the inductor and the chimney into the air-ducts and thence down to the lamp. With this construction sudden or strong gusts of wind are rendered harmless to the lamp, for they cannot pass directly into the globe, but on the contrary, are so deflected and directed that they can only pass into the air-ducts through which their passage is sufficiently tortuous to render them harmless to the flame.

Having described our invention, what we

claim as new therein, and desire to secure by Letters Patent, is—

1. In a lamp the combination with the inductor having the air-ducts extending therefrom, of a slotted chimney projecting within and of less diameter than said inductor, and a flaring or conical shield above and external to said inductor, substantially as and for the purpose set forth.
2. In a lamp, the combination with the inductor having air-ducts extending therefrom and an inwardly and downwardly turned oblique flange at the upper edge thereof, of a slotted chimney of less diameter than said in-

ductor and an outwardly flaring or conical shield above and external to said inductor, substantially as and for the purpose described.

3. In a lamp the combination with the inductor C, flange J, and the air-ducts E leading therefrom, of the chimney B, having the deflector H and the perforated flange F, and the flaring or conical shield K, substantially as and for the purpose described.

WILLIAM S. HAMM.
ANTHONY M. DUBURN.
